UNITED STATES PATENT OFFICE.

THOMAS C. ORNDORFF, OF WORCESTER, MASSACHUSETTS.

CARTRIDGE-BELT.

SPECIFICATION forming part of Letters Patent No. 399,924, dated March 19, 1889.

Application filed December 19, 1888. Serial No. 294,046. (No model.)

To all whom it may concern:

Be it known that I, THOMAS C. ORNDORFF, of Worcester, in the State of Massachusetts, have invented a new and useful Improvement 5 in Cartridge-Belts, of which the following is a specification.

My invention relates to a cartridge-belt or bandoleer made of woven material having the body of the belt and its thimbles or pockets woven in one piece. Such a belt, broadly 10 considered, is not new with me. Belts of this general character are set forth, for instance, in Letters Patent No. 193,613, of July 31, 1877, and Letters Patent No. 236,058, of December 15, 1880.

In the belt which I have devised the pockets are closed at one end, and the belt itself is a multiply fabric, generally and preferably a two-ply fabric, the pockets being formed 20 by the plies themselves, and those portions of the plies which intervene between the pockets being bound together into a solid homogeneous fabric. The weft or filling passes transversely of the fabric from one 25 edge of one ply across to the other edge, around the latter, and thence back to the opposite edge of the second ply, thence back from this last edge around the other edge, and thence back to the edge of the first ply from which 30 it started, and so on. In this way a double-ply-fabric belt is produced closed along one edge and open along the other edge, except at those portions between the pockets where the 35 two plies are united together from edge to edge by the binders. In this way a cheap, efficient, and readily-manipulated belt is produced, protecting the ball and its juncture with the shell from sand, dirt, bruises, and abrasion.

40 In the accompanying drawings, Figure 1 is a view of an extended belt made in accordance with my invention and containing no cartridges. Fig. 2 is a view of the same belt when filled with cartridges. Fig. 3 is a diagram of a section of a portion of the belt on a greatly-enlarged scale, the section being taken on line 3 3, Fig. 1. Fig. 4 is a diagrammatic section on like scale on line 4 4, Fig. 1.

45 The manner of weaving the belt will be 50 understood without explanation by those skilled in the art by reference to Figs. 3 and

4. The warps of the upper ply are lettered *a b* and those of the lower ply *c d*. The two series of binders which hold together the two plies and make them into one fabric between 55 the pockets are lettered *e f*. The weft is lettered *g*. Those portions of the fabric in which the binders do not extend through both plies form the pockets. The weft *g* is thrown by a shuttle in the usual way through the two 60 sheds of warp of the upper and lower plies, starting, for instance, in the upper shed from that edge of the fabric on which the open ends or mouths of the pockets are to be to the opposite edge, thence back through the 65 lower shed to the open edge of the fabric from which it first started, thence back through the lower shed to the closed edge, thence back through the upper shed to the open edge, and so on. In this way 70 the belt is woven with pockets formed by the two plies, open at one end and closed at the other, with a solid doubly-ply fabric between the pockets. These pockets may be woven of any desired size to fit the diameter 75 of any particular-sized individual cartridge; or still larger pockets may be woven to contain magazines or cases for magazine-guns—such, for instance, as the magazines or cases for the well-known Lee magazine-gun. The 80 size of the pockets depends upon the number of picks in the two sheds before the binders are brought in play in order to close them. The small pockets for individual cartridges and the larger pockets for magazines may be 85 woven in the same belt, the larger pockets being upon one portion of the length of the belt, and the smaller pockets being upon the remaining portion.

In case bottle-shaped cartridges are to be 90 used with the belt a suitable number of binder-picks can be thrown into and out of action before the others, so as to contract those portions of the pockets adjoining the closed ends in order to fit the contracted necks of the 95 cartridges. The belt is woven flat, as seen in Fig. 1. When, however, the cartridges are inserted in the pockets, the belt, when naturally extended, will take the shape shown in Fig. 2, having its greater length along its 100 closed edge. The result is that the belt, whether worn over the shoulder or around

the waist, will fit the person very much more easily and comfortably. This feature is one which characterizes no other woven pocketed cartridge-belt of which I have knowledge.

5 Having described my invention, what I claim as new, and desire to secure by Letters Patent, is as follows:

A cartridge-belt composed of multiply fabric, provided with cartridge-pockets integral

therewith formed by the plies and closed to along one edge of the fabric, as hereinbefore set forth.

In testimony whereof I have hereunto set my hand this 15th day of December, 1888.

THOMAS C. ORNDORFF.
